CHESTER W. CRUMBINE, OF ROCHESTER, NEW YORK, ASSIGNOR TO ELECTROMATIC TYPEWRITERS, INC., OF ROCHESTER, NEW YORK, A CORPORATION OF NEW YORK

FRACTIONAL LINE SPACER FOR TYPEWRITERS

Application filed December 13, 1928. Serial No. 325,621.

The object of this invention is to produce a fractional line spacing construction which shall be simple, compact and inexpensive, but convenient and reliable in operation.

To the foregoing end, the invention consists in a construction in which a novel form of clutch is employed, the clutch comprising a bowed leaf spring, bearing frictionally at its ends against a cylindrical clutch surface, together with means for increasing the curvature of the spring, so as to relieve the end pressure, when it is desired to cause relative rotary movement of the clutch members.

In the accompanying drawings, Fig. 1 is a longitudinal section of portions of the platen and associated parts, in a typewriting machine embodying the present invention. Fig. 2 is a partial longitudinal section, in a plane at a right angle to that of Fig. 1; and Fig. 3 is a sectional view, on the line 3-3 in Fig. 1, looking from right to left.

The invention is illustrated as embodied in and associated with a platen 5, of ordinary form, which is mounted, at its ends, in frame members 6 and 7 of the usual carriage. Knobs 8 and 9 are provided for operating the platen in the usual manner, together with a ratchet drum 10, which cooperates with the line-spacing means. These means are not shown, as they may be of any suitable or well known form.

At the right-hand end of the platen is the usual bushing 11, provided with a slotted bearing 12, to engage the frame member 6 and prevent endwise movement of the platen. The other end of the platen is supported by a bushing 13 of a form peculiar to the present invention. The supporting and controlling rod 14, which passes through the bushings in the usual manner, is provided, near the left-hand end of the platen, with a bearing collar 15 to engage the frame member 7. This collar may be loose upon the rod. The knobs 8 and 9 are fixed upon the ends of the rod 14 in the usual manner.

The present invention resides in the particular construction of the clutching means at the left-hand end of the platen, by which the bushing 13 is adjustably connected with the ratchet drum 10. The inner surface of

the rim of this drum is smoothly cylindrical, and the bushing has a cylindrical flange 16 which fits closely but freely within the drum. At diametrically opposite points the flange 16 is slotted, to receive the ends of a blade spring 17. The length and the normal curvature of this spring are such that it tends to straighten itself from the position shown in Fig. 3, and thus to press its ends forcibly against the cylindrical clutch surface of the drum 10, so as frictionally to resist rotation of the drum with respect to the bushing 13, and this frictional resistance is sufficient to prevent relative rotation of parts during the ordinary operation and the line-spacing movements of the platen. At a point adjacent the clutch spring 17, however, the rod 14 has a flattened surface 18, and by rotation of the rod this surface may be brought into engagement with the clutch spring, with the result that the spring is bent to a more curved position, so as to diminish its effective length and thus to relieve the pressure of its ends against the clutch surface.

In order that the knobs 8 and 9 may be used to turn the platen through full line-spacing angles without disengaging the clutch, the relative rotation of the rod and the bushing 13 is controlled by means comprising a cylindrical member 19, which is fastened in the bushing 13 by means of a pin 20. This cylinder 19 has two oppositely disposed recesses 21, which are engaged by a cross-pin 22 on the rod 14. A spring 23, interposed between the bushing and the pin 22, holds the parts normally in the position shown in the drawings, wherein the pin is in the narrow right-hand ends of the recesses 21. With the parts in this position, relative rotation of the rod 14 and the bushing 13 is positively prevented—thus preventing disengagement of the clutch, so that the knobs may be used to rotate the platen and the ratchet drum for full line-spacing movement.

When a fractional line-spacing movement is necessary, either of the knobs may be manipulated to slide the rod 14 from right to left, thus compressing the spring 23 and bringing the cross-pin 22 into engagement with the wider left-hand portions of the re-

cesses 21. The rod is then free to be rotated sufficiently to cause disengagement of the friction clutch, whereupon further rotation of the knobs and the rod, will turn the platen 5 through any desired angle, while the ratchet drum remains stationary under the influence of the usual line-spacing and retaining means. When the knobs are released the spring 23 forces the rod back to the normal 10 position illustrated, thus causing the cross-pin, through its engagement with the cam-like surfaces of the recesses 21, to rotate back to a position in which the clutch spring 17 is released and permitted to lock the parts 15 frictionally together.

The invention claimed is:

1. In a device of the class described, the combination with a cylindrical member and a ratchet wheel connected thereto for step-by-step rotation, of a clutch for releasably connecting the ratchet wheel to the cylindrical member, said clutch comprising an inner cylindrical surface on one of said parts, a bowed blade spring adapted to engage said clutch surface frictionally and retained against rotation relatively to the other part, and externally operable means for increasing the curvature of the spring in a direction transversely to the axis of said cylindrical member to relieve its pressure against the clutch surface.

2. In a device of the class described, the combination with a cylindrical member and a ratchet wheel connected thereto for step-by-step rotation, of a clutch for releasably connecting the ratchet wheel to the cylindrical member, said clutch comprising an inner cylindrical surface on one of said parts, a bowed blade spring adapted to engage said clutch surface frictionally and retained against rotation relatively to the other part, and an axial supporting rod for the cylindrical member having an actuating knob at its end and a cam surface arranged to engage 45 and bend the spring to disengage it from the clutch surface and permit rotation of the cylindrical member relatively to the ratchet wheel.

3. In a device of the class described, the combination with a cylindrical member and a ratchet wheel connected thereto for step-by-step rotation, of a clutch comprising an inner cylindrical clutch surface in said ratchet wheel, and a transversely arranged bowed 55 blade spring adapted to normally engage said surface, means projecting from said cylindrical member into engagement with the ends of said spring to prevent relative rotation between said spring and cylindrical 60 member, a rod mounted axially in said cylindrical member and having relative axial and longitudinal movement therein, a cam on said rod adapted to engage and bend the spring when the rod is turned relatively to the cylindrical member, and means interposed be-

tween the cylindrical member and the rod for holding the rod normally at one end of its range of longitudinal movement and retaining it against rotation relative to the cylindrical member.

4. In a clutch, the combination of a hollow cylindrical member, an end bushing therein, a ratchet wheel having an inner cylindrical clutch surface, a flange on said bushing projecting into said ratchet wheel and having opposite disposed slots, a bowed blade spring seated in said slots and normally engaging said clutch surface, an axial control rod movable longitudinally in said cylindrical member, a cam surface on said rod cooperative with said blade spring to bend the spring when the rod is manually actuated, a recessed inner projection on the bushing, a pin extending laterally from the control rod into engagement with the recess in said projection to limit relative rotation of the rod and cylindrical member, and a spring surrounding the rod within said projection and tending to move the rod longitudinally to its normal position disengaged from said blade spring.
